[57] CLAIM

The ornamental design for a combination telephone and answering set, as shown and described.

DESCRIPTION

FIG. 1 is a perspective view of the combination telephone and answering set showing my new design;

FIG. 2 is a top plan view thereof;

FIG. 3 is a bottom plan view thereof;

FIG. 4 is a top plan view of the telephone stand and a bottom plan view of the inverted handset spaced apart from the stand for clarity of illustration;

FIG. 5 is a front elevational view thereof;

FIG. 6 is a rear elevational view thereof;

FIG. 7 is a right side elevational view thereof; and

FIG. 8 is a left side elevational view thereof.
